[57] CLAIM

The ornamental design for a clock or similar article, as shown and described.

DESCRIPTION

FIG. 1 is a front elevational view of a clock or similar article showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof; and

FIG. 7 is a front elevational view of another embodiment of my new design of FIGS. 1-6;

FIG. 8 is a right side elevational view thereof;

FIG. 9 is a left side elevational view thereof;

FIG. 10 is a top plan view thereof;

FIG. 11 is a bottom plan view thereof; and

FIG. 12 is a rear elevational view thereof.
